GAUGING DEVICE

Edwin H. Birdsall, Golden, Colo., assignor to
Remington Arms Company, Inc., Bridgeport,
Conn., a corporation of Delaware

Application July 29, 1943, Serial No. 496,539

6 Claims. (Cl. 209—90)

The present invention relates to a gauging device, particularly for gauging the length of elongated articles, such for instance as cartridge shells, and has for an object to provide such a gauging device by means of which the articles are successively fed into relation with automatic gauging means and are selectively ejected, those articles of standard length or greater being ejected in one path to suitable receptacle means, while those articles of less than standard length are ejected in another path to suitable receptacle means. It is to be understood that by proper setting, the device also may be used to separate standard length articles from articles greater than standard length.

It is an object of the present invention to provide a gauging device which will not depend upon the human equation, but will separate all shells of greater than a predetermined length from short shells.

A further object is to provide a gauging device which may be adjusted with precision for the gauging of any predetermined standard length within a limited range.

Another object is to provide a gauging device which may be readily incorporated in present types of twin screw inspection machines, without appreciable alteration therein.

With the above and other objects in view, an embodiment of the invention is shown in the accompanying drawing, and this embodiment will be hereinafter more fully described with reference thereto, and the invention will be finally pointed out in the claims.

In the drawing:

Fig. 1 is a front elevation, partially broken away, of an inspection machine incorporating the gauging device, according to the illustrated exemplary embodiment of the invention, and showing one of the cartridge shells in its position as it is fed along the twin screw feed elements toward the gauging device.

Fig. 2 is an end elevation.

Fig. 3 is a plan view.

Fig. 4 is a detail plan view of the bracket support of the gauging device, removed from the machine, and with the parts normally supported thereby removed therefrom.

Fig. 5 is a perspective view of the end of the lower feed screw, showing the cam element of the gauging device attached thereto.

Fig. 6 is a perspective view of the cartridge shell guide element of the gauging device.

Fig. 7 is an end elevation showing a cartridge shell of sub-standard height in relation to the

gauging device and showing in dot-and-dash lines its position during ejection.

Fig. 8 is an end elevation showing a cartridge shell of normal height in relation to the gauging device and showing in dot-and-dash lines its positions during ejection.

Similar reference characters indicate corresponding parts throughout the several figures of the drawing.

- 10 Referring to the drawing, the twin screw inspection machine, shown by way of example, and with which the gauging device of the invention is incorporated, comprises a base 10 provided at its ends with vertical bearing standards 11 and 12, in which are journaled the ends of longitudinally extending twin screw elements 14 and 15, having their axes disposed in a plane at an angle of substantially 45° to the horizontal base, these twin screw elements being provided at one end with
- 15 meshing gears 16 and 17 respectively, driven by a drive pinion 18. The pitch of the upper screw is in opposite direction of the lower screw and preferably the concave screw channel of the upper screw is narrower than that of the lower screw.
- 20 Forwardly of the twin screw elements there is provided a horizontal mirrored guide 19, having its supporting base plate 19^a mounted upon brackets 20 and 21, and provided at its inner edge with a substantially 90° angle V-groove 22 having
- 25 its inner wall in a plane substantially at a 45° angle and in line with the bases of the screw channels of the twin screw elements, so that it supports the periphery of the circular heads of the cartridge shells A as they are transported by the
- 30 twin screw elements from one end to the other, while the other wall supports the end surfaces of the heads.
- 35

- 40 Adjacent the bearing standard 12, at a point where the cartridge shells complete their traverse along the twin screw elements, the gauging device of the invention is provided, the illustrated exemplary embodiment thereof comprising a supporting bracket consisting of a horizontal base bar 23, of rectangular cross-section, having secured
- 45 at its inner side adjacent its rearward end a vertical bar 24, provided near its upper end and upon its forward side with a forwardly projecting bearing extension 25. The base bar 23 is adapted to be secured to the base 10 of the machine by a screw 26.
- 50

- 55 Within a horizontal passage 27 in the bearing portion 25 there is engaged a lever supporting shaft 28, provided intermediate its ends with an integrally formed flange 29 bearing upon the outer surface upon the bearing portion 25, one

threaded end portion of the shaft extending through the passage 27 and being secured by a nut 30 bearing against a spacer washer 31. Upon its other threaded end portion, which projects outwardly from the flange 29 there is engaged a gauge lever 32 secured thereon by means of lock nuts 33—33, this lever being provided at its forward end with a downwardly projecting straight edge rib 34 of V-shape in cross section. The other end of the lever projects beneath a vertically disposed stop screw 35 adjustably screwed in a horizontally projecting lug 36 secured upon the bracket member 24, the screw being fixed in its adjusted position by means of a lock nut 37. The lever 32 is free to move upwardly in the event a malformed shell is passed through, so as to prevent damage to the gauging element. The lever is made of sufficient weight to return to an accurately located position and remain there when standard shells are gauged.

To the forward end of the base bar 23 there is secured a guide member 38 having at its inner marginal edge a V-groove 39, adapted to be positioned in exact continuation of the V-groove 22 of the mirrored guide, and extending beyond the end of the mirrored guide to the end of the twin screw elements and substantially forwardly in the transverse vertical plane of the gauging lever 32. The guide member is provided with a horizontal mounting bracket extension 40 having slots 41—41 and engaged upon the supporting base 19a of the mirrored guide, and to which it is secured by screws 42 engaged in the slots 41. The guide member may thus be rigidly and exactly aligned with the mirrored guide. After being secured in this manner to the bracket 21 the guide member is secured to the forward end of the base bar 23 by means of a vertical depending plate portion 43, provided with a slot 44, engaged by a head screw 45 screwed into the end of the base bar, this arrangement permitting the securing of the guide element without disturbing its aligned relation with the V-groove 22. The horizontal mounting portion 40 is provided at its outer edge with a longitudinally extending finger extension 46, disposed forwardly in the vertical plane of the gauge lever 32 and defining the forward side of an opening 47 in the guide member disposed forwardly of the V-groove therein.

Upon the end of the lower screw element 15 there is provided a projecting cam plate 48 in the form of a cylindrically curved triangular shaped member adapted to fit the cylindrical surface of the screw threads, its inner wall 49 being inclined to conform to the edge of the thread portion upon which it is engaged and being secured thereon by means of screws 50. The relatively wide forward shell-engaging surface 51 of the cam is parallel to the axis of the screw and is disposed in the vertical plane of the gauge lever 32.

The operation is as follows:

In operation the articles to be gauged, as for instance, the cartridge shells A, are placed with their head ends engaged in the mirror guide channel 22 and their side walls resting in inclined relation in the grooves of the twin screw elements 14 and 15, a succession of the articles in side-by-side relation being fed by the rotation of the screws from left to right along the mirror guide groove as shown in Figs. 1 to 3, wherein one of the cartridge shells is illustrated by way of example in feeding relation. As the cartridge shells reach the right-hand end of the screw elements, they move in the V-groove 39 of the guide element 38 and are

engaged by the rotating cam 48 of the lower screw element, which causes the shell to swing or pivot about its lower relatively heavy end supported within the V-groove, the inclination of the shell and the weight of its head end maintaining it in the groove as it pivots. The gauging rib 34 of the gauging lever 32 is disposed in relation to the arc of movement of the upper end of the swinging cartridge shell, so that in the case of one less than standard length, its upper end clears the gauging rib and thus continues in its swinging movement imparted thereto by the continued movement of the cam. As it swings over dead center, with its head end still engaged with the V-groove, its side wall comes into contact with the finger 46 at a point sufficiently near the head end so that the outer end overbalances the head end, the shell thereupon falling at the outer side of the finger, as indicated by the dot-and-dash lines in Fig. 7, 20 into a suitable receptacle, a suitable guide or chute means being preferably provided in relation to the finger.

In the case of a cartridge shell of standard length the cam swings the shell to the point where 25 its upper end contacts the gauging rib 34 of the gauge lever, thus arresting the swinging movement of the upper end, so that continued movement of the cam causes the lower head end of the cartridge shell to be swung outwardly about its upper end as a pivot to the point where it is disengaged from the V-groove 39, dropping over the edge of the groove downwardly through the opening 47, as indicated by the dot-and-dash lines in Fig. 8, 30 into a suitable receptacle. A suitable guide or chute means is preferably provided in relation to the opening 47.

In order to prevent jams it is preferable to locate the rib 34 relative to the V-groove 39 so that the plane of the mouth of the shell, which lies at 40 right angles to the axis of said shell, will be at an angle of less than 90° to the radius of rotation at the gauging point. The supporting edge for instance should be a predetermined distance from the center of the head, and on the opposite side of the center line from the side of the shell which engages the rib 34.

If desired the gauging operation may be carried out by similar apparatus upon cartridge shells to separate shells of shorter than standard length. 50 In this case the shells which clear the gauge lever and are ejected at the outer side of the finger 46 will be those of less than standard length, while those which engage the gauge lever and drop through the opening 47 will be acceptable shells of standard length. Two of the devices may be used together if desired.

The form of the invention illustrated in the drawing and described herein is typical and illustrative only, and it is evident that the invention is capable of embodiments in other forms, all falling within the scope of the appended claims.

What is claimed is:

1. In a gauging device, article supporting means adapted to pivotally support an article to be gauged in inwardly inclined relation, cam means arranged to engage and swing said article outwardly upon said supporting means as a pivot beyond the vertical dead center line, gauge means disposed in relation to the arc of swinging movement of said article at a point inwardly of said vertical dead center line adapted to contact an article of more than a predetermined length to arrest its swinging movement whereby continued movement of said cam means is adapted to disengage said article from said supporting means

to effect ejection in a given ejection path, an article unengaged by said gauge means adapted to continue its swinging movement whereby it is ejected in a different ejection path.

2. In a gauging device, article supporting means adapted to pivotally support an article to be gauged, movable actuating means arranged to engage and swing said article upon said supporting means as a pivot, gauge means disposed in relation to the arc of swinging movement of said article adapted to contact an article of more than a predetermined length to arrest its swinging movement whereby continued movement of said actuating means is adapted to disengage said article from said supporting means to effect ejection in a given ejection path contiguous to said supporting means, abutment guide means spaced from said supporting means a distance less than the length of the balancing point of said article from its supported end, an article unengaged by said gauge means adapted to continue its swinging movement into engagement with said abutment means whereby it is ejected in a different ejection path.

3. In a gauging device, longitudinally grooved article guide means adapted to pivotally support an article to be gauged, feed screw means parallel to said guide means adapted to feed said article in rearwardly inclined relation, cam means carried by said feed screw means arranged to engage and swing said article upon said guide means as a pivot, gauge means disposed in relation to the arc of swinging movement of said article adapted to contact an article of more than a predetermined length to arrest its swinging movement whereby continued movement of said cam means is adapted to disengage said article from said guide means to effect ejection in a given ejection path, an article unengaged by said gauge means adapted to continue its swinging movement whereby it is ejected in a different ejection path.

4. In a gauging device, longitudinally grooved article guide means, article supporting means having a guide groove in continuation of said guide means and adapted to pivotally support an article to be gauged, feed screw means parallel to said guide means adapted to feed said article

in rearwardly inclined relation, cam means carried by said feed screw means arranged to engage and swing said article upon said supporting means as a pivot, gauge means disposed in relation to the arc of swinging movement of said article adapted to contact an article of more than a predetermined length to arrest its swinging movement whereby continued movement of said cam means is adapted to disengage said article from said guide means to effect ejection in a given ejection path, an article unengaged by said gauge means adapted to continue its swinging movement whereby it is ejected in a different ejection path.

15 5. In a gauging device, cartridge shell supporting means adapted to pivotally support a shell to be gauged, a rotating cam actuating means arranged to engage and swing said shell upon said supporting means as a pivot, gauge means
20 disposed in relation to the arc of swinging movement of said shell adapted to contact a shell of more than a predetermined length to arrest its swinging movement by said cam whereby continued movement of said actuating means is
25 adapted to disengage said article from said supporting means to effect ejection in a given ejection path, a shell unengaged by said gauge means adapted to continue its swinging movement under the urgency of said rotating cam whereby it is
30 ejected in a different ejection path, said pivot and gauge means being located relative to each other so that the plane of the end of the shell adjacent the gauge is less than 90° relative to the radius of rotation of the article at point of engagement with the gauge.

6. In a gauging device, article supporting means adapted to pivotally support an article to be gauged, a gauge member spaced from said support and adapted to engage an overlength article, rotating actuating means disposed in operative position to swing said shell about said supporting means to discharge the same in one path should said article be engaged by said gauge so as to interrupt its swinging movement and into a second path should said article not be engaged by said gauge and is free to continue in its rotation by said rotating means.

EDWIN H. BIRDSALL.
